(57) CLAIM

The ornamental design for a shoe as shown and described.

DESCRIPTION

FIG. 1 is a bottom view of a shoe showing my new design; FIG. 2 is a bottom rear perspective view thereof; and, FIG. 3 is a bottom front perspective view thereof.

The broken lines immediately adjacent to the ends of the shaded groove area define the bounds of the claimed design and form no part thereof. The broken lines depicting the remainder of the shoe form no part of the claimed design.
